UNITED STATES PATENT OFFICE

JOSEPH GRISON, OF NEW YORK, N. Y.

REFRIGERATING DEVICE

Application filed June 15, 1929. Serial No. 371,080.

This invention relates to refrigerating apparatus of the type adapted to solidify carbon dioxide in small quantities as may be needed, and more particularly to means for automatically releasing and raising the cover for such apparatus.

There is now in use a portable apparatus by which carbon dioxide liquid may be solidified in small quantities for table use, or for use at soda fountains, etc. Such apparatus comprises a casing containing a large number of coils of copper tubing, the latter having one of its ends entering into a small chamber in which the liquid is solidified, and the other end of the tubing being connected to a valve for controlling the flow of the liquid from a supply tank.

The control valve is opened manually and held in such a position by a spring controlled latch, which is automatically released to close the valve when a quantity of the gas has been solidified and the pressure in the valve has reached a predetermined amount.

Heretofore, apparatus of this type has been provided with a cover which is clamped down tightly onto the casing during the solidifying process, and afterwards unclamped and manually raised to remove the product. The operation of clamping and unclamping the cover is a source of inconvenience, especially when the apparatus is operated frequently, such as when employed in soda fountains.

It is an object of this invention to provide a device for automatically unclamping and raising the cover of a carbon dioxide solidifying apparatus.

A further object is the provision of resilient means in the cover of such an apparatus for gripping a cup in which carbon dioxide is solidified in order to facilitate the removal and handling of the product.

These and other objects are attained by the novel construction, combination and arrangement of parts hereinafter described and shown in the accompanying drawing, constituting a material part of this disclosure and in which:

Figure 1 is a side view, partially sec-

tioned, of a carbon dioxide solidifying apparatus embodying my invention.

Figure 2 represents a front view of the structure shown in Figure 1, and

Figure 3 represents a plan view of the connection between the cover and the casing.

Referring to the drawing, the casing 3 of a carbon dioxide solidifying apparatus is provided with integral ears 4, in which is mounted a fulcrum pin 5, having pivotally mounted thereon the ears 6 integral with a cover 7.

A spring 8 is coiled about the pin 5, and has one end 9 engaging a lug 10 integral with the cover, for the purpose of normally urging the cover to rotate clockwise (Figure 1) to a raised position.

The front side of the cover has a small plate 11 fixed thereto by means of screws 12, the plate 11 having integral therewith or rigidly connected thereto a rod 13, which, when the cover is lowered as shown in Figure 1, extends parallel with the sides of the casing 3. The rod 13 has a right-angularly extending portion 14, adapted to be engaged by the handle 15, which has an integral stud journaled in a bushing 17 integral with the casing 3, the stud being loosely connected to the shaft 16 which extends into a valve block 18, and is adapted to control the opening and closing of the valve contained in block 18. (The valve not forming any part of this invention, is accordingly not shown.)

Projecting from block 18 is a pin 19 having fixed thereto one end of a spring 20 coiled about shaft 16, the other end of the spring being fixed to a pin 21 mounted on shaft 16.

Projecting from a lug 22 on block 18 is a pin 23, about which is coiled a spring 24 having one end fixed to pin 23, and its other end fixed to a latch 25 pivoted on pin 23. The latch 25 has a shoulder 26 adapted to engage a corresponding shoulder on a flange 27 integral with shaft 16, and the spring 24 tends to hold the latch constantly in a position to snap into engagement with flange 27.

The casing 3 and cover 7 are made of 100

suitable metal, and the cover 7 has a hard rubber lining 28, provided with a plurality of recesses in which are mounted resilient grips 29, adapted to resiliently hold a cup 30 in engagement with the cover 7.

5 In operation, the cup 30 is inserted in the cover 7 between the grips 29, and the cover lowered to the position shown in Figure 1. The handle 15 is then turned to the horizontal position as shown in Figure 2, during 10 which operation it engages the portion 14 of rod 13 and holds the cover tightly over the casing 3. At the same time the handle 15 rotates the shaft 16 to open the valve (not shown) in casing 18 to admit carbon 15 dioxide gas; and the latch 25, by engaging flange 27, holds the handle in the horizontal position.

The carbon dioxide gas passes through the 20 valve and through coiled tubing, (not shown) and in a well known manner is solidified in the cup 30. When a cake of solid carbon dioxide has been formed in the cup 30, the pressure in the valve block 25 18 increases to such an extent as to move the shaft 16 longitudinally until the flange 27 is slid from engagement with latch 25, at which time the spring 20 returns the handle 15 to a vertical position, and the spring 8 30 30 raises the cover 7 which carries upward with it the cup 30 held by the grips 29. The cup 30 and its contents may now be easily removed from the cover.

The foregoing disclosure is to be regarded 35 as descriptive and illustrative only, and not as restrictive or limitative of the invention, of which obviously an embodiment may be constructed including many modifications without departing from the general scope herein indicated and denoted in the appended claims.

Having thus described my invention what I claim as new and desire to secure by Letters Patent, is:

45 1. In a carbon dioxide freezing apparatus having a casing and cover hinged thereon, resilient means normally tending to raise the cover, a rod fixed to the cover and extending downwardly along the sides of the 50 casing, said rod having its lower end bent at an angle, a handle extending through the casing and positioned near the rod, means to normally urge the handle to a vertical position, said handle being adapted when in 55 a horizontal position to engage the angular portion of the rod to prevent raising of the cover, and means to latch the handle in a horizontal position.

60 2. In a carbon dioxide freezing apparatus having a casing and a cover hinged thereon, resilient means to raise the cover, a valve control handle rotatably mounted on the casing, means to normally hold the handle in a vertical position, means to latch the 65 handle in a horizontal position, and means

connected with the cover and engageable by the handle to hold the cover tightly down on the casing when the handle is in a horizontal position.

3. In a carbon dioxide freezing apparatus 70 having a casing and a cover hinged thereon, resilient means to raise the cover, a valve control handle rotatably mounted on the casing, and means connected with the cover and engaged by the handle to hold the cover down tightly on the casing.

4. In a carbon dioxide freezing apparatus 75 having a casing and a cover hinged thereon, said cover having a hard rubber lining with a plurality of recesses, and resilient grips 80 mounted in said recesses adapted to hold a cup on the cover.

5. In a carbon dioxide solidifying apparatus 85 having a casing with a cover hinged thereon, resilient means to raise the cover, a cup in which the carbon dioxide is solidified, resilient grips mounted in the cover to hold said cup, means to clamp the cover tightly on to the casing, and means to automatically release the cover when a quantity 90 of carbon dioxide has been solidified in said cup.

This specification signed this 14th day of June, 1929.

JOSEPH GRISON.
